DETACHABLE COLLAR CONSTRUCTION

Joseph Lorenz Koenig, Brilon, Germany, assignor to
Koenig & Uekermann, K.G., Bielefeld, Germany

Application June 29, 1954, Serial No. 440,206

Claims priority, application Germany January 22, 1954

1. Claim. (Cl. 2—124)

The present invention relates to garments, particularly day-shirts, provided with exchangeable collars and cuffs. 15

It is generally known that the exchangeable collars of day-shirts are fastened to the annular fastening rim at the neck-portion of the shirt either by means of studs, or by means of buttons fastened at one part and button-holes provided at the other part. It is further known that the sewed-on buttons usually become damaged or torn off during the washing and that the studs frequently get lost. It has, therefore, already been tried to substitute 20 for these button-closing-means, flap-like closing means. However, the way in which the flap-like closing means have so far been devised has been unsatisfactory regarding the reliable attachment of the collar to the fastening rim and for that reason were the cause of continuous trouble. For the detachable fastening of the cuffs the difficulties were even more pronounced, for which reason the use of exchangeable cuffs has in many cases already been abandoned.

Because of the quick soiling of collars and cuffs, shirts provided with exchangeable collars and cuffs are preferred by many people, although shirts provided with attached collars appear to be more comfortable in use.

Hence, the object of the invention is to overcome the deficiencies of known constructions and to provide a day-shirt with detachable collar and cuffs which is as comfortable in use as a shirt provided with attached collar and cuffs.

The present invention solves the problem by providing a garment, particularly a day-shirt having at least one detachable part, an annular fastening and at each connecting place with said detachable part as one element, said detachable part as another element, one of said elements to be detachable connected to one another being at least double walled and provided at a plurality of connecting points with pockets, the other element being provided at said connecting points with opposite fastening tabs having parallel side edges, consisting of textile material stiffened by chemical means, and fixed by several transverse rows of stitches near one end for holding the tabs closely to said element in a position for mutual co-operative self-holding action with said corresponding pockets, being made by sewing together portions of said double-walled parts to form recesses of like shape and dimensions as said corresponding tabs. The tabs consist preferably of an outer textile covering and one or a plurality of stiffening strips, wrapped up in that outer covering, whereby the stiffening strips may consist of textile strips suited for stiffening by chemical means and heat treatment, and of strips suited for the absorption of the chemical stiffening means.

Additional features and advantages of the present invention will be understood from a consideration of the following detailed description taken in connection with the accompanying drawings, forming a part of this specification and in which two embodiments of the invention have been shown by way of example. However, I wish to say that the invention is not confined to any strict

conformity with the showing of the drawings, but may be changed or modified, so long as such changes or modifications mark no material departure from the salient features of the invention as expressed in the appended claim.

In the accompanying drawings, in which like parts are referred to by the same reference numerals,

Fig. 1 is a fractional view of a day-shirt provided with detachable turn-down collar and cuffs;

Fig. 2 is a cross-section on line II—II of Fig. 1;

Fig. 3 is a fractional view of a day-shirt similar to that of Fig. 1, but having the flap-like fastening means arranged at the collar in a different way;

Fig. 4 shows in outstretched position a cuff detachably fastened to the lower end of a sleeve;

Fig. 5 is a cross-section on line V—V of Fig. 4;

Fig. 6 is a cross-section on line VI—VI of Fig. 4;

Fig. 7 shows the essential parts of a plug strip prior to being stitched together;

Fig. 8 shows the plug strip of Fig. 7 stitched together and provided with a plurality of longitudinally extending rows of stitches;

Fig. 9 shows the flap-like fastening member ready for being stitched onto the collar and cuffs.

Referring now to the drawings in detail, the reference numeral 1 designates the shirt, while 2 is the annular neck portion of the shirt to which the turn-down collar 3 is attached. Detachably fastened to the lower end of the sleeve 4 is the cuff 5. The collar 3 and the cuff 5 are provided on the outside of their inner fastening portions 13, 14 with fastening flaps 6 adapted for engagement in pockets 7 formed at the inner side of the annular neck portion 2 and of the fastening portion 8 of the sleeve 4. The fastening flaps 6 and appertaining pockets 7 are arranged near the ends of the collar 3 as well as the cuffs 5 and near the vertical center line of the collar and cuffs. The flaps or tabs 6 have a width approximately the same as the pockets and a length substantially equal to the depth of the pockets to provide a close fit. The appertaining pockets 7 are formed at the neck portion 2 and sleeve portions 8 through circum-sewing of portions of the double-walled fastening portions 2 and 8 through the provision in the circum-sewed portions of slots provided with reinforced edges in button-hole-like fashion. All of the fastening flaps 6 and appertaining pockets 7 extend in the collar 3 of the embodiment of Fig. 1 transversely of the longitudinal direction of the collar, while in the cuffs 5 of the same embodiment the flaps and pockets extend at the ends of the cuffs 5 transversely of the longitudinal direction and between the two ends in longitudinal direction of the cuffs 5. If between the ends of the cuffs 5 a plurality of flaps 6 are arranged they should preferably extend in opposite directions. It is further feasible to arrange the flaps 6 between the two ends of the cuffs 5 in such a way that they extend in alternately longitudinal and transverse direction, whereby then merely the longitudinally extending flaps 6 should extend in opposite directions with respect to each other.

Fig. 2 shows a cross-section of the collar 3 and annular neck portion 2 on line II—II of Fig. 1.

Fig. 3 shows an embodiment in which the flaps 6 positioned near the ends of the collar extend in transverse direction, while the flaps 6 at the back of the collar 3 extend both from the vertical center line of the collar 3 in longitudinal direction, and in opposite directions with respect to each other, toward the ends of the collar 3.

Fig. 4 shows the end of the sleeve 4, with the cuff 5 detachably fastened to it, in outstretched position, while Figs. 5 and 6 show cross-sections of the cuff 5 and sleeve portion 8 on lines V—V and VI—VI of Fig. 4. Here, the flaps 6 positioned near the middle of the cuff 5 extend in opposite directions toward the ends of the cuff 5,

whereby unintended loosening of the flaps 6 from their appertaining pockets at the sleeve portion 8 is rendered very difficult.

The fastening flaps 6 are formed from a linen strip 9, having twice the width of the flaps, an acetate silk strip 10 of slightly smaller width, and a cotton band 11 having the width of the flaps. These parts are placed on top of each other (as shown in Fig. 7), then longitudinally folded up, then stitched together at the edges, and then provided with a plurality of parallel longitudinally extending rows of stitches 12, as shown in Fig. 8. The band-like strip thus obtained is then impregnated with acetone and methylc alcohol in a moist-press, whereby the artificial threads of the acetate silk become dissolved, and then dried and stiffened in a hot-press. From a strip produced in this way the individual flaps 6 are separated through punching, cutting or the like, with a round edge at one of their ends, whereupon the opposite end is fastened by two transverse rows of stitches 15 to the collar 2 or cuff 5.

What I claim as new and desire to secure by Letters Patent of the United States is:

In combination with a shirt, a detachable member, a fastening member, and means for attaching said detachable member to said fastening member, said means comprising a plurality of pockets disposed angularly with respect to each other on one of said members, each of said pockets having a straight slit-opening at one end and having co-extensive straight parallel secured sides, flat uniformly thin non-bent locking tabs for insertion 30 into said pockets lying entirely on the one surface of the other of said members which abuts the pocket carry-

ing surface of said one of said members, each of said tabs being secured to said other member transversely across one end only and having the major portions of its length and its other end unsecured, said line of transverse securing being parallel to said straight slit-opening when a tab is inserted into a pocket, each of said tabs having a width approximately the same as its corresponding pocket to provide a tight fit when inserted therein and the unsecured end portion of each of said tabs having a 10 length substantially equal to the depth of its corresponding pocket, the entire length of each of said tabs aligned in the direction of insertion into its corresponding pocket, the unsecured end of each of said tabs having rounded portions for easy insertion of said tab into its 15 corresponding pocket, said unsecured end of each of said tabs and the surface of said other member to which it is secured gripping the edge of its corresponding pocket when a tab is inserted into its respective pocket, each of said tabs having a plurality of rows of longitudinal reinforcements extending along the length thereof, and said tabs having a chemical stiffener associated therewith.
